FIG. 1

FIG. 2

SEGREGATION OF STREAMS FOR THE PRODUCTION OF AMMONIA

FIELD OF THE INVENTION

The present application relates to a method for recovering ammonia present in a sour water stream containing odiferous compounds such as pyridines, indoles, ketones and mercaptans produced during an upgrading process for upgrading bitumen from oil sands into synthetic crude. The present application further relates to a method of upgrading bitumen wherein ammonia present in waste streams produced during the upgrading of bitumen is recovered and used to remove SO_2 from flue gas prior to its release into the atmosphere, thereby resulting in an upgrading method that is more self-subsistent.

BACKGROUND OF THE INVENTION

Oil sand deposits such as those found in the Athabasca Region of Alberta, Canada, contain a significant amount of heavy oil or bitumen. One recovery method that has been successful in extracting the heavy oil or bitumen from oil sand is commonly referred to as the hot water process and involves the liberation of the bitumen from the sand by forming oil sand slurry with hot water and separating the bitumen by froth flotation to form a bituminous froth. The bitumen present in the froth is then concentrated by diluting it with a solvent such as naphtha after which the diluted froth is centrifuged to remove substantially all of the water and mineral solids. Naphtha is then removed and the bitumen is ready for further upgrading to produce a synthetic crude oil.

Bitumen is a complex and viscous mixture of large or heavy hydrocarbon molecules which contain a significant amount of sulfur, nitrogen and oxygen. In order for bitumen to be processed in refineries, it must first be broken up into smaller hydrocarbon molecules (synthetic crude oil). Unlike the more useful smaller hydrocarbon molecules, bitumen is carbon rich and hydrogen poor. Thus, upgrading of bitumen to synthetic crude oil generally involves removing some carbon while adding additional hydrogen to make more valuable hydrocarbon products. This is generally done using four main processes: coking, which removes carbon and breaks large bitumen molecules into smaller parts; distillation, which sorts mixtures of hydrocarbon molecules into their components; catalytic conversions, which help transform hydrocarbons into more valuable forms; and hydrotreating, which is used to help remove sulfur and nitrogen and add hydrogen to molecules. The synthetic crude oil end product can then be further refined into jet fuels, gasoline and other petroleum products.

As mentioned, a useful process for upgrading bitumen is delayed or fluid coking. With fluid coking, the bitumen feedstock is introduced into a fluid coker reactor containing a fluidized bed of hot solids, preferably coke, and is distributed uniformly over the surfaces of the coke particles where it is cracked to vapors and to carbonaceous material which is deposited onto the particles. The vapors pass through cyclones which remove most of the entrained coke particles. The vapor is then discharged into a scrubbing zone where remaining coke particles are removed and the products are cooled to condense heavy liquids.

The coke particles in the coking zone flow downwardly to a stripping zone at the base of the coker reactor where a stripping gas, such as steam, is used to remove interstitial product vapors from, or between, the coke particles, as well as some adsorbed liquids from the coke particles. The coke particles are then removed to a burner where sufficient air is

injected for burning at least a portion of the coke and heating the remainder sufficiently to satisfy the heat requirements of the coking zone where the unburned hot coke is recycled. Net coke, above that consumed in the burner, is withdrawn as product coke.

10 Coking produces a large amount of "sour water", so called because of the large amount (e.g., between 0.3 and 10.4 wt %) of hydrogen sulfide (H_2S) present therein. Also present in the sour water is a large amount (e.g., between 0.3 and 6.0 wt %) of ammonia (NH_3). Another process for upgrading bitumen is catalytic cracking, which also produces sour water having significant quantities of H_2S and NH_3 . Catalytic cracking involves the use of catalytic crackers operated at moderately-high temperatures (e.g., 400-500° C.), where a catalyst such as a zeolite catalyst is added to aid in "cracking" or splitting the large hydrocarbon molecules into smaller hydrocarbon molecules. It would be desirable to be able to recover the NH_3 present in either coking sour water or catalytic cracking sour water, as NH_3 is a valuable and useful product.

20 For example, during typical fluid coking operations, fuel gas produced in the coker burner is typically treated in a CO burner. However, the flue gas that is produced in the CO burner contains high levels of SO_2 and thus it is undesirable to 25 release the flue gas directly into the atmosphere without addressing the high levels of SO_2 first. One process that may be used to remove SO_2 from flue gas is flue gas desulfurization, which process uses anhydrous or aqueous ammonia which reacts with the SO_2 to produce ammonium sulfate (see, for example, Canadian Patent No. 2,343,640, U.S. Pat. No. 4,690,807 and U.S. Pat. No. 5,362,458). The ammonium sulfate so produced can then be used as a fertilizer. Thus, flue gas desulfurization not only removes the SO_2 present in the flue gas but also produces a valuable byproduct, namely, ammonium sulfate.

30 However, significant quantities of NH_3 are needed in flue gas desulfurization, which can prove to be very costly. Thus, it would be desirable to recover NH_3 from sour water streams 35 produced during bitumen upgrading to synthetic crude that is of a sufficient quality so that it could be used in such a process. It is understood, however, that the NH_3 recovered from sour water streams could also be used directly to make other useful products such as fertilizers and the like.

SUMMARY OF THE INVENTION

40 In one broad aspect, the present application relates to a method for recovering NH_3 present in a sour water stream 45 containing odiferous compounds such as pyridines, indoles, ketones and mercaptans produced during an upgrading process for upgrading bitumen from oil sands into synthetic crude, comprising:

50 55 treating the sour water stream in a sour water treatment unit to produce a NH_3 -rich stream and a H_2S -rich stream; and

60 65 hydrotreating the NH_3 -rich stream in a hydrotreater in the presence of hydrogen to remove the odiferous compounds such as pyridines, indoles, ketones and mercaptans and produce a treated NH_3 -rich stream.

In one embodiment, the sour water stream is produced 65 during a fluid coking operation. In another embodiment, the sour water stream is produced during a catalytic cracking operation. In another embodiment, the odiferous compounds are ketones such as acetone and 4-mercapto-4-methyl-2-pentanone.

3

In one embodiment, the method further comprises: removing other impurities such as residual H₂S from the treated NH₃-rich stream in an ammonia purification unit to produce cleaned NH₃.

In another embodiment, the method further comprises: treating the treated NH₃-rich stream in a second sour water treatment unit prior to ammonia purification in the ammonia purification unit.

The cleaned NH₃ that is recovered from the sour water produced during a fluid coking operation by the above method can be used to treat SO₂-rich flue gas that is also produced in such operation. Thus, in another aspect, a method for recovering NH₃ present in a sour water stream containing odiferous compounds such as pyridines, indoles, ketones and mercaptans produced during a bitumen upgrading process is provided, comprising:

feeding the bitumen to a fluid coking unit comprising a fluidized bed coker, a coke burner and a CO burner, and producing a hydrocarbon product stream, the sour water stream, and a SO₂-rich flue gas stream;

treating the sour water stream in a sour water treatment unit to produce a NH₃-rich stream and a H₂S-rich stream;

hydrotreating the NH₃-rich stream in a hydrotreater in the presence of hydrogen to remove the odiferous compounds such as pyridines, indoles, ketones and mercaptans and produce a treated NH₃-rich stream;

removing other impurities such as residual H₂S from the treated NH₃-rich stream in an ammonia purification unit to produce cleaned NH₃; and

treating the SO₂-rich flue gas stream with the cleaned NH₃ in a flue gas desulfurization unit to remove SO₂ from the flue gas stream and produce ammonium sulfate.

In another aspect of the present application, a bitumen upgrading process is provided, wherein ammonia from segregated sour water streams produced during upgrading is recovered, comprising:

feeding the bitumen to a fluid coking unit comprising a fluidized bed coker, a coke burner and a CO burner, and producing a first hydrocarbon product stream, a first sour water stream and a SO₂-rich flue gas stream;

hydrotreating the first hydrocarbon product stream in a first hydrotreater in the presence of hydrogen to produce a second hydrocarbon product stream and a second sour water stream;

treating the second sour water stream in a first sour water treatment unit to produce a first NH₃-rich stream and a first H₂S-rich stream;

removing impurities such as residual H₂S from the first NH₃-rich stream in an ammonia purification unit to produce cleaned NH₃; and

treating the flue gas stream with the cleaned NH₃ to remove the SO₂ in the flue gas in the form of ammonium sulfate prior to releasing the flue gas into the atmosphere.

In one embodiment, the bitumen upgrading process further comprises:

treating the first sour water stream in a second sour water treatment unit to produce a second NH₃-rich stream and a second H₂S-rich stream;

hydrotreating the second NH₃-rich stream in a second hydrotreater in the presence of hydrogen to remove odiferous compounds such as pyridines, indoles, ketones and mercaptans and produce a treated NH₃-rich stream; and

removing impurities such as residual H₂S from the treated NH₃-rich stream in the ammonia purification unit to produce cleaned NH₃.

4

In one embodiment, the treated NH₃-rich stream is first treated in the first sour water treatment unit prior to ammonia purification in the ammonia purification unit.

In one embodiment, the bitumen upgrading process further comprises:

treating the first sour water stream in a second sour water treatment unit to produce a second NH₃-rich stream and a second H₂S-rich stream;

combining the second NH₃-rich stream with the first hydrocarbon product stream prior to hydrotreatment in the first hydrotreater to remove odiferous compounds such as pyridines, indoles, ketones and mercaptans.

DESCRIPTION OF THE DRAWINGS

The foregoing and other features of the application will become apparent to those skilled in the art to which the present application relates upon reading the following description with reference to the accompanying drawings, in which:

FIG. 1 is a schematic flow diagram showing an embodiment of a method for recovering NH₃ present in a sour water stream containing odiferous compounds such as pyridines, indoles, ketones and mercaptans produced in a bitumen upgrader.

FIG. 2 is a schematic flow diagram of a bitumen upgrading process of the present invention which incorporates the method for recovering NH₃ as shown in FIG. 1.

DESCRIPTION OF THE PREFERRED EMBODIMENTS

It was initially thought that both the sour water stream from a fluid coking reactor and the sour water stream from a hydrocarbon hydrotreater could be used to produce the ammonia for use in treating flue gas produced during fluid coking. However, when both sour water streams were combined, the ammonia obtained therefrom produced a very strong and very foul odor when used to treat the flue gas prior to its released into the atmosphere. It was discovered that the foul odor was caused by 4-mercaptop-4-methyl-2-pentanone, also known as "cat-ketone". This compound has a very potent off-odor which resembles the smell of cat urine. Parts per million (ppm) quantities of 4-mercaptop-4-methyl-2-pentanone released into the atmosphere can be detected as far as 20 km from the source.

Further studies by the present applicant determined that the originating source of the 4-mercaptop-4-methyl-2-pentanone was the sour water stream from the fluid coking reactor. Significant levels of both acetone and 4-mercaptop-4-methyl-2-pentanone were detected in this sour water stream. Further, it was discovered that these ketones, and, in particular, 4-mercaptop-4-methyl-2-pentanone, were being carried over into NH₃-rich streams that were produced when the sour water was treated in a sour water treatment unit. Thus, when the NH₃ was further purified in a NH₃ purifier for use in treating flue gas, the resultant ammonia was also found to be contaminated with 4-mercaptop-4-methyl-2-pentanone. Without being bound to theory, it is believed that the acetone present in the sour water stream is eventually converted into 4-mercaptop-4-methyl-2-pentanone as follows:

Thus, use of sour water from the coker reactor for ammonia production resulted in ammonia contaminated with 4-mercaptop-4-methyl-2-pentanone. However, if the NH_3 -rich stream is first treated in a hydrotreater in the presence of hydrogen, the resultant treated NH_3 -rich stream could then be used to produce ammonia essentially free from odorous ketones such as 4-mercaptop-4-methyl-2-pentanone. The reducing hydrogen in the presence of a catalyst may convert the ketones into alcohols, thereby destroying any acetone, which can be converted into 4-mercaptop-4-methyl-2-pentanone, and any 4-mercaptop-4-methyl-2-pentanone that may already be present, hence, eliminating the odor problem. In the alternative, ketones present may be converted to water and a residual hydrocarbon.

On the other hand, tests on the sour water stream produced during treatment of a hydrocarbon stream in a hydrotreater showed that little or no acetone and/or 4-mercaptop-4-methyl-2-pentanone was detectable. This is likely due to the fact that any acetone present would be destroyed during the hydrotreating process prior to being converted to 4-mercaptop-4-methyl-2-pentanone and that any 4-mercaptop-4-methyl-2-pentanone present would also be destroyed during hydrotreating. Thus, it was discovered that only the first sour water stream from the coker reactor resulted in contaminated ammonia which produced the foul odor when used to treat flue gas prior to its release.

Hence, it was discovered that in order to use certain sour water streams produced during bitumen upgrading to produce ammonia without a cat urine-like odor, one must either first hydrotreat the ammonia obtained from sour water (i.e., sour water produced from a fluid coking unit or a catalytic cracker) or only use sour water streams produced from a hydrotreater, which is substantially free of 4-mercaptop-4-methyl-2-pentanone, to produce ammonia, or both. The ammonia thus obtained could then be used in flue gas desulfurization, without causing the problem of the strong cat urine-like odor being released into the atmosphere.

FIG. 1 is a schematic flow diagram showing an embodiment of the invention. In particular, FIG. 1 is a schematic of a method for recovering NH_3 present in a sour water stream containing ketones produced during an upgrading process for upgrading bitumen from oil sands into synthetic crude. Bitumen is fed into bitumen upgrader 110, which upgrader can be a fluid coking unit, a catalytic cracker, or the like. Sour water 112, which contains ketones such as acetone, 4-mercaptop-4-methyl-2-pentanone, or both, is then treated in a sour water treatment unit to separate the H_2S from the NH_3 present therein.

The sour water treatment unit comprises a first stage stripper, H_2S stripper vessel 140, and a second stage stripper, ammonia (NH_3) stripper vessel 50. H_2S stripper vessel 140 is

a steam-reboiled distillation column which distills the sour water 112 to produce a H_2S -rich vapor stream 142 and a stripped sour water stream 144, the bottoms stream containing all of the ammonia. Stripped sour water stream 144 is then fed into ammonia stripper vessel 50, which is a refluxed distillation column. Ammonia stripper vessel 50 then distills the stripped sour water stream 144 to produce an ammonia-rich vapor stream 152. It is understood that other methods could be used for removing ammonia and H_2S from sour water, for example, the process disclosed in U.S. Pat. No. 4,486,299, incorporated herein by reference.

The ammonia-rich vapor stream 152 is then condensed in condenser 154 prior to being hydrotreated in hydrotreater 180 in the presence of hydrogen and a catalyst as known in the art, for example, CoMo and NiMo, to produce treated ammonia-rich stream 182. Treated ammonia-rich stream 182, which has been scrubbed from the gas phase with water, is optionally treated in another conventional sour water treatment unit, for example, by first treating it in H_2S stripper 240 to remove H_2S and then in NH_3 stripper 250. The further treated ammonia-rich stream 252 is then purified in NH_3 purifier 160. The NH_3 purifier can be a one- or two-stage scrubbing system which removes any residual H_2S and other impurities.

FIG. 2 is a schematic of a typical bitumen upgrading process showing how ammonia obtained in the present invention can be used to treat flue gases produced during fluid coking. Bitumen obtained from oil sand and steam is introduced into the pyrolysis or coking zone of fluid coker reactor 10, which 15 contains fluidized solids such as coke particles so that the bitumen is heated to form vaporized liquid oil products. The vaporized products are passed through a cyclone (not shown) to remove entrained solids which are returned to the coking zone. The vapors leave the cyclone and pass into a scrubber 20 region (not shown) of the coker reactor 10 and coker hydrocarbon product stream 16 is removed for further upgrading. Also produced in the fluid coking process in coker reactor 10 is 20 sour water 12, which contains a high concentration of ammonia and hydrogen sulfide (H_2S).

40 Coke produced in coker reactor 10 is deposited on the fluidized solids (e.g., coke particles) present therein and the coked solids 14 are then heated in coker burner 20 in the presence of oxygen to form hot coked solids. The hot solids from the coker burner are introduced into fluid coker 10 to 45 supply heat for the pyrolysis of bitumen (not shown). Also produced in the coker burner is flue gas, which contains high levels of SO_2 .

The coker hydrocarbon product stream 16, which still contains a substantial amount of sulfur and nitrogen, is further 50 upgraded in a hydroprocessor, for example, hydrotreater 30, where H_2 and catalysts, such as CoMo, NiMo, and zeolites, are added to hydrogenate aromatic hydrocarbons and remove the sulfur and nitrogen containing heteroaromatic hydrocarbons to 55 yield a treated hydrocarbon stream containing reduced sulfur and nitrogen. The hydrotreater sour water 32, which contains the H_2S and ammonia separated from the hydrotreating reaction effluent, is further treated to remove H_2S and ammonia in a sour water treatment unit.

In the embodiment shown in FIG. 2, the sour water treatment 60 unit comprises a first stage stripper, H_2S stripper vessel 40 and a second stage stripper, ammonia (NH_3) stripper vessel 50. H_2S stripper vessel 40 distills the sour water 32 to produce an H_2S -rich vapor stream 42 and a stripped sour water stream 44. Stripped sour water stream 44 is then fed directly into ammonia stripper vessel 50. Ammonia stripper vessel 50 then distills the stripped sour water stream 44 to produce an ammonia-rich vapor stream 52.

The ammonia-rich vapor stream **52** from ammonia stripper vessel **50** is then sent to ammonia purification unit **60**. Ammonia purification unit **60** may comprise a first stage water scrubber and a second stage water scrubber, where the ammonia-rich vapor stream is further stripped of residual H₂S and other contaminants such as mercaptanes to produce cleaned ammonia **62**. It is understood that other ammonia purification units and processes known in the art could be used.

The cleaned ammonia **62** can then be used to remove SO₂ from the flue gas **22** produced in coker burner **20** by using a gas-liquid contactor or other type of flue gas scrubber in a process commonly referred to as wet flue gas desulfurization (see, for example, Canadian Patent Nos. 2,343,640, 2,116, 949, 2,344,494, 2,384,872, 2,371,004 and 2,180,110, incorporated herein by reference). Thus, with reference to FIG. 2, flue gas **22** and cleaned ammonia **52** are each fed into gas-liquid contactor **70**, where the ammonia is allowed to react with the SO₂ to produce ammonium sulfate. The ammonium sulfate is a valuable product which can be used as a fertilizer and the like.

As in FIG. 1, the coker sour water **12** can be treated in H₂S stripper **140** to remove H₂S from the sour water and produce stripped sour water stream **144**. Stripped water stream **144** is fed into NH₃ stripper vessel **150** to produce ammonia-rich vapor stream **152**. Ammonia-rich vapor stream **152** is then condensed in condenser **154** prior to hydrotreatment in hydrotreater **180**. It is understood, however, that condensed ammonia-rich vapor stream **152** could also be combined with first hydrocarbon stream **16** and hydrotreated in hydrotreater **30**.

Treated ammonia-rich stream **182** is optionally then treated in H₂S stripper **40** and NH₃ stripper **50** prior to being purified in NH₃ purifier **60**. In the alternative, ammonia-rich stream **182** can be fed directly into ammonia purification unit **60**.

The previous description of the disclosed embodiments is provided to enable any person skilled in the art to make or use the present invention. Various modifications to those embodiments will be readily apparent to those skilled in the art, and the generic principles defined herein may be applied to other embodiments without departing from the spirit or scope of the invention. Thus, the present invention is not intended to be limited to the embodiments shown herein, but is to be accorded the full scope consistent with the claims, wherein reference to an element in the singular, such as by use of the article "a" or "an" is not intended to mean "one and only one" unless specifically so stated, but rather "one or more". All structural and functional equivalents to the elements of the various embodiments described throughout the disclosure that are known or later come to be known to those of ordinary skill in the art are intended to be encompassed by the elements of the claims. Moreover, nothing disclosed herein is intended to be dedicated to the public regardless of whether such disclosure is explicitly recited in the claims.

We claim:

1. A method for recovering NH₃ present in a sour water stream containing odiferous compounds comprising pyridines, indoles, ketones and mercaptans produced during an upgrading process for upgrading bitumen from oil sands into synthetic crude, comprising:

- (a) subjecting the bitumen to an initial upgrading step comprising either coking in a coker or catalytic cracking in a catalytic cracker to produce the sour water stream containing the odiferous compounds;
- (b) treating the sour water stream in a sour water treatment unit to produce a NH₃-rich stream, a H₂S-rich stream and a treated water stream; and

(c) removing the odiferous compounds from the NH₃-rich stream to produce cleaned NH₃ that is of a sufficient quality to be used in a flue gas desulfurization process without producing a foul odor.

5 2. The method as claimed in claim 1, wherein the coking operation is a fluid coking operation.

3. The method as claimed in claim 1, wherein the odiferous compounds are removed from the NH₃-rich stream by hydrotreating the NH₃-rich stream in a hydrotreater in the 10 presence of hydrogen and a catalyst to produce a hydrotreated NH₃-rich stream.

4. The method as claimed in claim 3, further comprising:

(d) removing other impurities comprising residual H₂S from the hydrotreated NH₃-rich stream in an ammonia purification unit to produce cleaned NH₃.

15 5. The method as claimed in claim 1, wherein the odiferous compounds are ketones comprising acetone and 4-mercaptop-4-methyl-2-pentanone.

6. The method as claimed in claim 4, further comprising:

(e) treating the hydrotreated NH₃-rich stream in a second sour water treatment unit prior to purification in the ammonia purification unit.

20 7. A method for recovering NH₃ present in a sour water stream containing odiferous ketones produced during an upgrading process for upgrading bitumen from oil sands into synthetic crude, comprising:

(a) feeding the bitumen to a fluid coking unit comprising a fluidized bed coker, a coke burner and a CO burner, and producing a hydrocarbon product stream, the sour water stream, and a SO₂-rich flue gas stream;

(b) treating the sour water stream in a sour water treatment unit to produce a NH₃-rich stream containing odiferous ketones, H₂S-rich stream and a treated water stream;

(c) hydrotreating the NH₃-rich stream in a hydrotreater in the presence of hydrogen to remove the odiferous ketones and produce a hydrotreated NH₃-rich stream; and

(d) removing other impurities such as residual H₂S from the hydrotreated NH₃-rich stream in an ammonia purification unit to produce cleaned NH₃;

40 wherein the cleaned NH₃ is of a sufficient quality to be used to treat the SO₂-rich flue gas stream in a flue gas desulfurization unit to remove SO₂ from the flue gas stream and produce ammonium sulfate without producing a foul odor.

45 8. The method as claimed in claim 7, wherein the odiferous ketones are acetone, 4-mercaptop-4-methyl-2-pentanone, or a combination of acetone and 4-mercaptop-4-methyl-2-pentanone.

9. The method as claimed in claim 7, further comprising:

(e) treating the hydrotreated NH₃-rich stream in a second sour water treatment unit prior to purification in the ammonia purification unit.

10. A process for upgrading bitumen and recovering cleaned ammonia (NH₃) from segregated sour water streams

55 produced during upgrading, said cleaned NH₃ being of a sufficient quality to be used in a flue gas desulfurization process without producing a foul odor, comprising:

(a) feeding the bitumen to a fluid coking unit comprising a fluidized bed coker, a coke burner and a CO burner, and producing a first hydrocarbon product stream, a first sour water stream containing odiferous compounds comprising pyridines, indoles, ketones and mercaptans and a SO₂-rich flue gas stream;

(b) hydrotreating the first hydrocarbon product stream in a first hydrotreater in the presence of hydrogen to produce a second hydrocarbon product stream and a second sour water stream;

- (c) treating the second sour water stream in a first sour water treatment unit to produce a first NH₃-rich stream, a first H₂S-rich stream and a first treated water stream;
- (d) treating the first sour water stream in a second sour water treatment unit to produce a second NH₃-rich stream containing the odiferous compounds, a second H₂S-rich stream and a second treated water stream;
- (e) hydrotreating the second NH₃-rich stream containing the odiferous compounds in a second hydrotreater in the presence of hydrogen and a catalyst to remove the odiferous compounds and produce a hydrotreated NH₃-rich stream; and
- (f) removing impurities comprising residual H₂S from the first NH₃-rich stream and the hydrotreated NH₃-rich stream in an ammonia purification unit to produce cleaned NH₃.

11. The process as claimed in claim 10, further comprising:

- (g) treating the SO₂-rich flue gas stream with the cleaned NH₃ to remove the SO₂ in the flue gas in the form of ammonium sulfate prior to releasing the flue gas into the atmosphere.

12. The process as claimed in claim 10, wherein the odiferous compounds are ketones comprising acetone and 4-mercapto-4-methyl-2-pentanone.

13. The method as claimed in claim 1, wherein the step of hydrotreating the NH₃-rich stream in a hydrotreater further comprises adding a catalyst.

14. The method as claimed in claim 13, wherein the catalyst is CoMo or NiMo.

15. The process as claimed in claim 10, wherein the first hydrotreater and the second hydrotreater are a single hydrotreater.

16. A process for recovering NH₃ from sour water streams produced during upgrading of bitumen from oil sands, said NH₃ being of a sufficient quality to be used in a flue gas desulfurization process without producing a foul odor, comprising:

- (a) feeding the bitumen to a fluid coking unit comprising a fluidized bed coker, a coke burner and a CO burner, and producing a first hydrocarbon product stream, a first sour water stream containing one or more odiferous compounds comprising pyridines, indoles, ketones and mercaptans and a SO₂-rich flue gas stream;
  - (b) hydrotreating the first hydrocarbon product stream in a first hydrotreater in the presence of hydrogen and a catalyst to produce a second hydrocarbon product stream and a second sour water stream;
  - (c) combining the first sour water stream and the second sour water stream to produce a combined sour water stream and treating the combined sour water stream in a sour water treatment unit to produce a NH₃-rich stream containing the one or more odiferous compounds and a H₂S-rich stream; and
  - (d) removing the one or more odiferous ketones from the NH₃-rich stream to produce a ketone-free NH₃-rich stream.
17. The process as claimed in claim 16, further comprising:
- (e) removing impurities comprising residual H₂S from the odiferous compound-free NH₃-rich stream in an ammonia purification unit to produce cleaned NH₃.
18. The process as claimed in claim 16, wherein the catalyst is CoMo or NiMo.
